[54] DISPLAY UNIT FOR CONFECTIONERY ITEMS

[76] Inventor: Enrique Bernat Fontlladosa, Paris St., No. 184, 4th Floor, Barcelona, Spain

[] Term: 14 Years

[21] Appl. No.: 949,379

[22] Filed: Oct. 6, 1978

[51] Int. Cl. .... D20—02

[52] U.S. Cl. D6/157; D6/24; D6/25; D6/188

[58] Field of Search .... D6/20, 23—25, D6/27—29, 85, 157, 181, 184, 186, 188—190; 211/13, 126, 128, 129, 131, 133, 134, 135, 163

[56] References Cited

U.S. PATENT DOCUMENTS

D. 235,595	7/1975	Dogliotti	D6/24
D. 236,768	9/1975	Dogliotti	D6/24
D. 236,771	9/1975	Dogliotti	D6/24
D. 252,481	7/1979	Gordon	D6/24
3,865,247	2/1975	Neglia	211/128

Primary Examiner—Barbara J. Bullock
 Attorney, Agent, or Firm—John E. Lind

[57] CLAIM

The ornamental design for a display unit for confectionery items, substantially as shown.

DESCRIPTION

The sole FIGURE is a perspective view of a display unit for confectionery items showing my new design; the rear and side opposite that shown are identical to the front and side shown and the base is flat and unornamented.

U.S. Patent

Feb. 24, 1981

Des. 258,334